(57)

CLAIM

The ornamental design for a sperm sampler, as shown and described.

DESCRIPTION

FIG. 1.1 is a front view of a sperm sampler;
FIG. 1.2 is a back view thereof;
FIG. 1.3 is a left view thereof;
FIG. 1.4 is a right view thereof;
FIG. 1.5 is a top view thereof;
FIG. 1.6 is a bottom view thereof; and
FIG. 1.7 is a perspective view thereof

(Continued)

The broken line areas as showing portions of the sperm sampler form no part of the claimed design.

1 Claim, 7 Drawing Sheets
